ICE RETAINER FOR WATER PITCHERS

Filed Sept. 9, 1929

INVENTOR.
Frank Pelletier
BY *John H. Blackley*
ATTORNEY

UNITED STATES PATENT OFFICE

FRANK PELLETIER, OF NEW YORK, N. Y.

ICE RETAINER FOR WATER PITCHERS

Application filed September 9, 1929. Serial No. 391,296.

This invention relates to new and useful improvements in an ice retainer for water pitchers.

When a water pitcher is filled with water and chopped ice, and is carried by its handle, strains are communicated to the wrist of the carrier. This is generally known, and the cause is that it is off balance. When the water is poured from the pitcher then the off balance is of advantage in that the pitcher may be readily tilted, but during carrying it would be advisable to carry the pitcher by a top handle instead of the side handle provided thereon.

15 The invention proposes a vertical spring for urging the sections of an ice retainer apart and arranged so that when the ice retainer is applied within the top opening of a pitcher, the vertical spring also acts to provide a handle for carrying. It is contemplated to arrange the spring at the center so that the pitcher will be in perfect balance when carried thereby. Vertical friction-material covered prongs are arranged on the periphery of the ice retainer for holding the latter element within a pitcher and for holding the pitcher upon the ice retainer when the spring is used as a carrying handle. The prongs are arranged to provide for the self aligning of 20 the ice retainer when inserted within a pitcher.

The invention also proposes the provision of a device of the class mentioned which is of simple durable construction, dependable in 25 use and efficient in action, and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawing forming a 45 material part of this disclosure:—

Fig. 1 is a perspective view of a pitcher with the device.

Fig. 2 is a plan view of the device, per se.

Fig. 3 is an enlarged fragmentary vertical 50 sectional view taken on the line 3—3 of Fig. 2.

Fig. 4 is a fragmentary vertical sectional view of the pitcher shown in Fig. 1, and illustrating the ice retainer in elevation.

Fig. 5 is a fragmentary vertical sectional view taken on the line 5—5 of Fig. 2. 55

Fig. 6 is a view similar to Fig. 2 but disclosing a device constructed according to the same invention but of modified form.

Fig. 7 is another view similar to Fig. 2 but illustrating a modification thereof. 60

Fig. 8 is a vertical sectional view taken on the line 8—8 of Fig. 7.

Fig. 9 is a fragmentary view of a portion of Fig. 7 showing another embodiment thereof.

Fig. 10 is a fragmentary vertical sectional view taken on the line 10—10 of Fig. 9. 65

Fig. 11 is a fragmentary elevational view showing a further development of the supporting handle.

Fig. 12 is a sectional view taken on the 70 line 12—12 of Fig. 11.

The reference numeral 12 indicates a conventional pitcher having a handle 13 and a mouth 14 diametrically opposite the handle. An ice retainer 15 is engaged within 75 the pitcher near its top and is of the type that expands for retaining its position. A strong vertical spring 16 accomplishes the expanding of the sections of the ice retainer and consists of a pair of vertical arms 17 each 80 formed with transverse loops 18 constituting finger grips, and a top longitudinal loop 19 connecting the arms 17. This spring simultaneous with its expanding action constitutes a support handle for the pitcher. 85

The said ice retainer 15 consists of a pair of substantially adjacent semi-circular discs 20 and 21 touching the transverse loops 18. These discs are slightly spaced one above the other so as to be relatively slidably. The straight sides of the semi-circular discs are aligned with each other so that both together substantially form a complete circle. Each of the disc sections is formed with a plurality of perforations 22 for the passage of water. 90

The disc sections are slidably connected with each other for movements at right angles to their straight sides, and this is attained by lugs 23 from each disc section projecting in opposite directions from their inner edges 100

and formed with superimposed slots 24. Rivets 25 loosely engage thru the superimposed slots and conclude the connection for slidably holding the disc sections.

5 The vertical spring 16 is attached upon the disc sections at right angles to the straight sides. This may be seen from an inspection of Fig. 2. One of the arms of the spring 16 is attached at its bottom upon one of the sections, and the other of the arms upon the other of the sections. A plurality of vertical prongs 26 connect with the periphery of the disc sections and have inturned free ends 27. Rubber or other friction tubes 28 are engaged upon the prongs and held against displacement by the inturned ends. Since the prongs 26 are vertical the outer elements of the rubber tubes are also vertical, and when the retainer is engaged within a pitcher 20 the vertical elements of the tube act against the sides of the pitcher and serve to properly align it in a substantially horizontal position.

In Fig. 2 four prongs 26 have been illustrated. These prongs are equally spaced around the periphery of the circle formed by the disc sections. In Fig. 6 six of these prongs have been illustrated. These prongs similarly are spaced at equal distances from 33 each other. In other respects the device is similar to the one illustrated in Fig. 2.

In Figs. 7 and 8, a modified form has been illustrated in which a pair of plates 29 and 30 are formed with points 31 and with one 35 straight side. These plates together form a star shape. They are slidably connected with each other by lugs 32 projecting from the inner edges and formed with slots 33 engaged by loose rivets 34. The plate 29 is located 40 directly above a semi-disc 20, and the plate 30 directly above a semi-disc 21.

The semi-discs 20 and 21 are constructed similar to the ones illustrated in Fig. 2, that is they are provided with opposite directed 45 lugs having slots and slidably connected by rivets. Similar numerals indicate corresponding parts to those shown in Fig. 2. The spring 16 is arranged for simultaneously urging the plates and the semi-discs apart. 50 This is accomplished by the bottom ends of the arms of the springs engaging thru the plates and the semi-discs and held there by nuts 35.

Each of the points 31 terminate in vertical 55 prongs 26 and rubber tubes 28 engage upon these prongs. The spring 16 serves to urge the elements apart so that the tubes 28 engage against the inner sides of a pitcher. The advantage of this construction is that the semi-discs may be replaced by larger or smaller 60 ones, or for ones having larger or smaller perforations and used with the same star shaped plates. For accomplishing the change over, nuts 35 are engaged upon the 65 lower ends of the arms 17 of the spring and

serve to hold the semi-discs in place. A removal of these nuts will permit the complete perforated disc structure to be removed and replaced as stated.

In Figs. 9 and 10, each of the points 31' 70 has been illustrated provided with a universal joint 36. Bent prongs 37 connect with the universal joint 36 and are shaped so that they have a vertical portion 38 with its center of gravity in line with the plane of points 75 31'. The universal joint is frictionally stiff and maintains the prongs from bending down. A rubber tube 28 is mounted upon each of the vertical portions of the bent prongs. When this retainer is engaged within a pitcher, the outer elements of the tubular rubber member 28 seek aligned positions with the inner sides of the pitcher irrespective of the inclination thereof. It is merely necessary to insert the retainer haphazardly 80 within the pitcher and the alignment is accomplished automatically.

In Figs. 11 and 12 a locking arm 40 is shown hinged to sleeve 41 as at 42. The sleeve 41 may be either loosely placed on one of the vertical arms 17 or it may be secured thereto. A V shaped notch 43 in locking arm 40 is adapted to engage the other vertical arm 17 and to keep the two arms 17 apart after the ice retainer 15 is placed 95 within the pitcher 12 and to prevent accidental falling out of the ice retainer when a large piece of ice suddenly impinges with the ice retainer 15. When the locking arm 40 is forced into engaging position as shown 100 in Fig. 11, the ice retainer 15 is held securely in position and the pitcher 12 may be lifted by inserting the finger in loop 19.

This type of locking arm may be used in all the forms of ice retainers disclosed.

In operation of the device, the sections of the various ice retainers may be forced together by manually squeezing the arms of the spring together along the finger grip loops 18. In this condition, the device may be engaged within a pitcher or removed from a pitcher. The spring 16 is very strong so that when engaged in a pitcher, the latter element though filled with water and ice may be safely carried by the spring 16 and if so desired the safety locking arm 40 may be forced into engagement and act as a handle. For pouring the water the conventional handle 13 of the pitcher may be used.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. An ice retainer comprising a pair of

semi-circular discs with their straight sides substantially adjacent each other, means for slidably connecting the disc sections to move at right angles to the straight sides, friction-
5 material covered vertical prongs connected with the edges of the disc sections for engaging against the inner sides of a pitcher, and a vertical spring for urging the disc sections apart and constituting a handle for supporting
10 a pitcher in which the retainer is engaged.

2. An ice retainer comprising a pair of semi-circular discs substantially adjacent each other, means for slidably connecting the
15 disc sections, friction-material covered vertical prongs connected with the edges of the disc sections for engaging against the inner sides of a pitcher, and a vertical spring for urging the disc sections apart and constituting
20 a handle for supporting a pitcher in which the retainer is engaged.

3. An ice retainer comprising a pair of semi-circular discs with their straight sides substantially adjacent each other, means for
25 slidably connecting the disc sections to move at right angles to the straight sides, friction-material covered prongs connected with the edges of the disc sections for engaging against the inner sides of a pitcher, and a vertical spring for urging the disc sections apart and constituting a handle for supporting
30 a pitcher in which the retainer is engaged.

4. An ice retainer comprising disc sections substantially adjacent each other, means for
35 connecting the disc sections to move away from each other, friction-material covered vertical prongs connected with the edges of the disc sections for engaging against the inner sides of a pitcher, and means for urging
40 the disc sections apart and constituting a handle for supporting a pitcher in which the retainer is engaged.

In testimony whereof I have affixed my
signature.

FRANK PELLETIER.
